CLAIM

The ornamental design for a loudspeaker, as shown and described.

DESCRIPTION

FIG. 1 is a front perspective view of a loudspeaker, showing our new design;

FIG. 2 is a partially enlarged view thereof, taken from FIG. 1;

FIG. 3 is a top plan view thereof;

FIG. 4 is a partially enlarged view thereof, taken from FIG. 3;

FIG. 5 is a front elevational view thereof;

FIG. 6 is a partially enlarged view thereof, taken from FIG. 5;

FIG. 7 is a rear elevational view thereof;

FIG. 8 is a bottom plan view thereof;

FIG. 9 is a partially enlarged view thereof, taken from FIG. 8;

FIG. 10 is a right side elevational view thereof; and, FIG. 11 is a left side elevational view thereof.

The broken lines in the figures illustrate portions of the design that form no part of the claimed design. The dot-dash broken lines of FIGS. 1-6, 8 and 9 are included to show partially enlarged views only and form no part of the claimed design. None of the broken lines form any part of the claimed design.
